UNITED STATES PATENT OFFICE.

REINHOLD WILHELM, OF SOUTH MELBOURNE, VICTORIA, AUSTRALIA, ASSIGNOR TO THE COMMONWEALTH WHITE LEAD & PAINTS PROPRIETARY LIMITED, OF MELBOURNE, AUSTRALIA, A COMPANY REGISTERED UNDER THE LAWS OF THE STATE OF VICTORIA.

MANUFACTURE OF LEAD COMPOUNDS.

Application filed September 24, 1925. Serial No. 58,357, and in Australia March 30, 1925.

This invention relates to the manufacture of lead compounds and more particularly to the manufacture of lead oxides (massicot and red lead), carbonates of lead and sulphates of lead.

The primary object of the invention is to obtain, with economy and safety, an intermediate compound of lead in such form that it can be readily converted into the final lead compounds of high purity suitable for the manufacture of pigments of great covering capacity, the manufacture of flint glass and, in general, for commercial purposes where a high grade product is required.

15 In the production of lead monoxide (PbO) preparatory to its conversion into lead compounds it is known to subject metallic lead to the action of heat in the presence of a blast or current of air, the lead being converted to a finely divided powder and carried away in the air current from which it is separated, mainly as lead monoxide, and collected for subsequent treatment by selected re-agents to form the required 25 lead compounds.

Owing to the injurious effect of lead or its compounds upon the health of the operatives if the dust is inhaled or absorbed into the system and also on account of economy, 30 it is highly desirable to prevent any escape of the powder of lead or its compounds. It is also advantageous, in converting the lead into the desired compounds, that a relatively large area of the lead should be exposed to 35 the re-agents in order that the latter may react thoroughly with the lead.

The present invention provides a process which fulfills these conditions and enables a high grade product to be obtained with 40 expediency. The invention in its broad aspect, comprises the production of a briquette from dust-sized particles of partly-oxidized lead (which may be wholly or partially converted thereafter into partly-oxidized and 45 hydrated lead) and which will be referred to hereinafter as "partly-oxidized lead dust", or simply as "dust", these particles being separated from each other in the briquette by minute spaces which may be occupied by 50 air, water, re-agents or reaction products, and the subsequent treatment of the briquettes by selected re-agents according to

the nature of the product required. The briquettes are of such formation as to allow thorough and effective penetration by the 55 desired re-agent without the need for agitating machinery or devices, which, when employed in such operations have been liable to cause escape of dust and consequent contamination of the atmosphere and also 60 absorb a considerable amount of power.

The temperature to which the metallic lead is heated to effect pulverization is, in accordance with this invention, so low and the rate of conversion of the lead into dust 65 is so rapid that contamination of the lead by the material constituting the apparatus is negligible.

The mode of dividing or reducing the metallic lead into dust, according to this invention, is such that the possibility of the dust escaping to the atmosphere is eliminated owing to the fact that the vessel or dust producer in which pulverization takes place is under a slightly negative pressure 70 relative to the atmospheric pressure. That is to say the air current is induced into and through the dust producer in such a manner as to positively prevent the loss of any dust. This fine dust is preferably mixed with 75 water to form a coherent mass which may be moulded or pressed into briquettes, which, for the production of certain compounds, may or may not be aged as hereinafter described, and suitably treated for the production 80 of the specified lead compounds.

From the period at which the dust is formed to the stage whereat it is moulded into the briquettes, the dust is contained within a leak proof system or within a system wherein all leaks are inward; and as the dust is in the form of a moist coherent mass when it arrives at the moulding station, there is not any free dust liable to escape and contaminate the atmosphere. The 90 briquettes so produced rapidly harden or set and may be easily handled with the least possible danger to the operatives, whilst they have been found to be readily permeable to re-acting mediums.

100 In order to ensure the best results it is desirable that the briquettes are so shaped that any particle thereof is within about half an inch of a free or exposed surface

so as to allow effective and thorough penetration of the re-agents.

The utilization of the partly-oxidized lead dust in the form of the said briquettes is an important feature of the invention. For instance if, in the manufacture of red lead, (Pb_3O_4) the lead dust was placed in a roasting furnace, only a comparatively thin layer of the dust could be used to secure proper conversion unless agitators or stirrers were employed. If the dust was introduced in thicker layers, stirring or agitating devices would be necessary to enable effective penetration of the re-agents, and there would always be a possibility of the dust being scattered so that collecting devices would be required for its recovery.

In the transformation of metallic lead to lead monoxide (massicot PbO) and red lead (Pb_3O_4) there should be a gain in weight of approximately 7% and 10% respectively; therefore, with proper supervision and efficient dust collecting devices the cost of conversion according to this invention should be largely, if not wholly, compensated for by this increase.

It is well known that the highest grade of red lead is a material known as orange mineral or orange lead and this is usually obtained by roasting white lead (normally $2PbCO_3 \cdot Pb(OH)_2$) at a temperature below dull red heat (not higher than $550^\circ C.$) and such a result is achieved by the present invention by roasting the briquettes at a temperature below dull red heat (not higher than $550^\circ C.$) after they have been aged.

But in order that this invention may be better understood reference will now be made to the accompanying drawings which are to be taken as part of this specification and read herewith, and which illustrate, somewhat diagrammatically, a preferred form of apparatus for use in this invention:

Figure 1 is a part sectional elevation of a suitable apparatus for reducing or dividing lead into dust, collecting the dust and mixing water therewith to form a plastic mass suitable for moulding into briquettes in accordance with the present invention.

Figure 2 is a cross sectional view of a rotary drum or container in which the lead is reduced to dust form as an initial step in the production of lead compounds.

Figure 3 indicates a suitable type of press for moulding the hydrated lead dust into briquettes.

Figure 4 is a perspective view of a briquette of a preferred formation in accordance with the invention.

Figure 5 is a vertical sectional view of the briquette.

Figure 6 is a part sectional elevation showing a suitable muffle furnace wherein the briquettes may be converted into desired compounds such as litharge and red lead.

Figure 7 is a chart in which the process for producing briquettes, formed from partly-oxidized lead dust, for conversion into specific lead compounds is indicated step by step.

In carrying out the invention metallic lead (see Figure 7) is pulverized at A by the action of heat in the presence of a current of air, which latter carries the particles of lead dust away in suspension. The dust is precipitated from the air current at B and is mixed with water at C to form a plastic, coherent mass. The coherent mass is then moulded at D into briquettes of a suitable shape which are allowed to set or harden at E. For conversion into certain lead compounds the briquettes are first aged at F before treatment by the appropriate re-action agents, whilst for other compounds the briquettes do not require to be aged prior to treatment by re-action agents.

For example, aged briquettes may be subjected to heat treatment in the presence of air as indicated at G and H for conversion, respectively, into lead monoxide PbO (massicot) and red lead Pb_3O_4 . To produce lead sulphates the briquettes are aged and may then be subjected to acid treatment as indicated at J. For carbonates of lead and certain other lead compounds, however, unaged briquettes are used and they may be exposed to suitable re-action agents as indicated at K L M respectively.

According to the form of apparatus shown for carrying out the invention, metallic lead is introduced into the interior of a rotatable drum or cylinder 2 which may be supported by rollers 3 and provided with a toothed or sprocket wheel 4 whereby it may be rotated. The drum is suitably housed within a furnace 6 which may be oil fired as indicated at 7. The lead is preferably introduced into the drum 2 by way of a feed opening 8 at one end, and if desired the lead may be fed into the drum in a molten condition from a melting bath or receptacle 9 suitably disposed as to be heated by the furnace gases or products of combustion. A feed pipe 11 leads from the bath 9 to conduct the molten lead by way of the feed opening 8 into the drum. A manually operable valve 12 may be interposed in the feed pipe 11 in order to enable the rate of feed to be controlled and adjusted as desired.

The rotatable drum, which may be constructed of cast iron or other suitable material, is preferably provided with a series of longitudinal partitions or ribs 13 which are spaced at circumferential intervals around the inner wall of the drum and form troughs 14. The ribs 13 project inwardly from the inner wall in a direction that is between a radial and a tangential direction.

The rotary drum is heated by the furnace to a temperature above the melting point of

lead (but not so highly as to form massicot in quantity as this quantity-formation would tend to choke up the drum and thus would interfere with the proper working 5 of the process) and the rotation of the drum causes the lead mass to be carried around in the troughs 14 and raised to such a position that the lead mass overflows or runs out of the troughs and falls by gravity to the bottom 10 of the drum. Air is induced through the feed opening 8 of the drum 2 and caused to pass longitudinally through the drum 2 and out of an outlet opening 16 at the other end to one or a series of dust separators or 15 collectors as will be more fully referred to hereafter. Thus the streams of lead mass which fall from the troughs as aforesaid are in the direct passage of the induced air current, whereby minute particles thereof are 20 carried in suspension by the air current from which they are precipitated in the dust collectors to a fine dust or impalpable powder. The direction of the air current through the drum 2 and the dust collectors is indicated 25 by arrows in Figure 1.

To provide for the separation and collection of the minute dust particles a stationary conduit or fitting 17 may be suitably supported in order to register with the outlet 30 opening 16 of the drum and this conduit may have a branch leading to a first or primary dust collector 18 into which the heavier particles of lead in the air current may fall by gravity. This first dust collector is preferably provided with an air inlet aperture 35 19 through which atmospheric air is induced into the conduit, the provision of this air inlet minimizing the liability of any of the lighter particles of lead dust falling into the first collector. It will be evident that the air entering this inlet aperture 19 will prevent the dust escaping from the first collector into the atmosphere so that perfect 40 safety is ensured. The relatively heavy particles of dust collected in the first collector may be returned to the rotary drum 2 for further treatment at desired intervals.

Another branch of the conduit 17 may be 50 suitably connected as at 20 to a second dust collector 21, which may also be connected by a conduit 22 to a third dust collector 23, a suitable suction fan 24 being arranged to ensure a current of air passing through the drum and the dust collectors. It is to be 55 understood that I do not wish to limit myself to the precise arrangement of dust collectors herein described and illustrated and that a greater or lesser number thereof may be employed as desired.

The dust precipitated by the collectors is 60 preferably delivered into a casing 26, the interior of which forms a combined conveying and mixing chamber 27 wherein the dust is mixed with water and conveyed to a briquette forming station. Accordingly

the dust collectors 21 and 23 may have delivery openings 28 which register with apertures 29 formed in the said casing 26. A screw conveyor 31 may extend longitudinally of the casing, suitable means being 70 provided to rotate the conveyor at the required speed.

Water may be injected by a suitable pump 32 through a feed pipe 33 to the chamber 27 wherein it is mixed with the dust by the 75 action of beaters or vanes 30 carried by the conveyor spindle 34 preferably adjacent the outer or delivery end of the chamber 27 to thereby form a coherent mass of a consistency suitable for pressing or moulding into 80 briquettes.

The pump 32 may be suitably driven from the screw conveyor spindle 34 and means 85 may be provided to regulate the rate of feed of the water in accordance with the amount of dust entering the mixing chamber.

From the mixing chamber 27 the moistened dust is delivered to a press or a moulding apparatus 35 indicated diagrammatically in Figure 3 which is adapted to mould it into 90 briquettes of the desired formation. The briquettes 36 may be made in the form of flat blocks or they may be of cylindrical form or again they may be made in the nature of rods of a limited diameter, but it is advisable that, whatever shape is imparted to the briquettes, any particle thereof should be within about one half an inch from a free or exposed surface to allow thorough penetration 95 of the re-acting agents. The briquettes are preferably moulded into the form of rectangular blocks (Figures 4 and 5) and are perforated by a series of through passages 37, whilst the exposed surfaces may, if desired, be provided with channels 38 as shown. 100

In instances where it is necessary for the briquettes to be subjected to heat in order to bring about their conversion into the required product (for example in the production of red lead, Pb_3O_4) it is advisable that the dimensions of the passages 37 and the body of the briquette should be so proportioned as to permit proper radiation of the heat from the briquette, as otherwise local high temperature may prevail, causing fusion of a 110 part of the briquette and thus preventing effective penetration of the re-acting agents. A briquette 5" by 4" by 2½" with evenly spaced perforations 37 and channels 38, has 115 been found very suitable for carrying out the invention and is of convenient size and weight for handling. 120

The dust, when moistened with water and moulded into briquettes as aforesaid, tends 125 to become heated and the briquettes speedily set or harden. Upon exposure to moisture, they are inclined to turn greyish in colour owing to the formation of hydrate and carbonate of lead. In other words they 130 turn partially into a kind of white lead, and

this probably accounts for the high quality of the red lead produced by the invention.

The briquettes may be used as such or may be aged according to the nature of the product desired; thus, in the production of white lead, ageing is not essential, but if an unaged briquette be used in the production of red lead or litharge, the resulting action may be so rapid as to render heat control difficult, 10 and result in an unsatisfactory product.

If desired the briquette may be aged by exposure to air with or without the addition of moisture, or if desired the ageing may be conducted by exposing the briquettes to warm 15 moist air exhausted from drying chambers. It has been found, however, that the ageing is generally more thorough and complete when the briquettes are exposed to ordinary atmospheric air.

20 When the briquettes are to be used for the production of red lead, Pb_3O_4 , they may be first aged and then treated preferably in a cast iron muffle furnace 41, (Figure 6) at a temperature of not higher than 550° C.

25 Air is admitted through an inlet 42 at one end of the muffle furnace and an air exhaust flue 43 is provided at the other end. The briquettes may be arranged in end to end formation (with slight spaces between adjacent briquettes) upon suitable trays 44 adapted for insertion into the furnace in such manner that the perforations 37 of the series of briquettes undergoing treatment are aligned, thereby providing longitudinal passageways for the air which is thus allowed to penetrate thoroughly into the briquettes. The inlet 42 of the furnace may be fitted with a door or closure 46 having apertures 47, and a suitable regulator 48 may be associated herewith to control the admission of air according to requirements. A damper 49 may also be interposed in the air exhaust flue 43 for a like purpose. The furnace may if desired be oil fired as indicated at 51 and 35 the products of combustion may be caused to follow a tortuous path as indicated by the arrows for the purpose of ensuring even heat distribution relative to the furnace 41.

40 The numeral 52 indicates a discharge vent 50 through which the combustion gases may pass into a suitable discharge stack. The air exhaust flue may be connected to the discharge stack near its lower or inner end to ensure a satisfactory draught or current 55 of air through the furnace 41.

When the burning or roasting treatment is completed the briquettes are removed and can be readily ground into fine powder for commercial use.

60 I have found that aged briquettes produced as aforesaid after only four hours roasting at a temperature not higher than 550° C. (for example, about 490° C.) contain 80% red lead, and that, by roasting the 65 aged briquettes at a higher temperature,

complete conversion to yellow lead monoxide (massicot) is effected in less than two hours.

Where it is desired to produce white lead (white carbonate of lead) the briquettes, with or without initial ageing, may be converted by the "Dutch" or "stack" method, the briquettes being preferably stacked so that the perforations thereof provide a series of substantially vertical passageways for the circulation and penetration of the reaction gases.

70 To produce lead sulphates from the briquettes, by the inter-action of sulphuric acid, it is essential that the briquette should be completely aged prior to such treatment.

75 It will, however, be understood that the treatment to which the briquettes, whether aged or unaged, may be subjected for conversion into the various lead compounds or salts will vary according to the particular product desired, but these conversion processes will generally conform to known methods for converting metallic lead or lead oxides into the various salts, and, as such, need not be further described except to state that the briquettes may or may not be "aged" 80 prior to conversion.

85 Having now described my invention what I claim as new and desire to secure by Letters Patent is:—

90 1. A process for manufacturing lead compounds which consists in mixing dust-sized particles of partly-oxidized lead with water to produce a plastic mass; forming a briquette therefrom; and thereafter converting such briquette into the required final lead compound by subjecting it to reactionary treatment.

95 2. In a process for manufacturing lead compounds, the steps of pulverizing metallic lead to a fine dust by the action of heat in the presence of a current of air, precipitating the particles of dust from the air current, mixing the precipitated dust with water to form a coherent mass, and shaping said mass into briquettes for conversion into the required final lead compounds by reactionary treatment.

100 3. A process for manufacturing lead compounds, which consists in pulverizing metallic lead to a fine dust by the action of heat in the presence of a current of air, precipitating the particles of dust from the air current, mixing the precipitated dust with water to form a coherent mass, shaping said mass into briquettes, ageing the briquettes by exposure to air, and subjecting the aged briquettes to reactionary treatment for conversion into the required final lead compounds.

105 4. A briquette for use in the manufacture of lead compounds, composed of dust-sized particles of hydrated, partly-oxidized lead separated from each other by minute spaces, the briquette being of such formation that 110

95

any one of said dust-sized particles therein is within about half an inch of a free or exposed surface of the briquette.

5. In the manufacture of lead compounds, the steps of mixing dust-sized particles of partly-oxidized lead with water to form a plastic mass, and shaping such mass into briquettes for subsequent reactionary treatment.

10 6. In the manufacture of lead compounds, the step of shaping a coherent mass of dust-sized particles of partly-oxidized metallic lead into briquettes for subsequent reactionary treatment.

15 7. In the manufacture of lead compounds, the step of shaping a coherent mass of dust-sized particles of partly-oxidized pig or

metallic lead into briquettes for subsequent reactionary treatment, such briquettes having passages through them so that any particle in a briquette is within about half an inch of a free or exposed surface of the briquette. 20

8. In the manufacture of lead compounds, the steps of mixing dust-sized particles of partly-oxidized lead with water to form a plastic mass, and shaping such mass into briquettes for subsequent reactionary treatment, such briquettes having passages through them so that any particle in a briquette is within about half an inch of a free or exposed surface of the briquette. 25 30

In testimony whereof I affix my signature.
REINHOLD WILHELM.
